UNITED STATES PATENT OFFICE.

RALEIGH J. ADAMS, OF CHICAGO, ILLINOIS.

BOILER.

Application filed September 14, 1922. Serial No. 588,189.

My invention relates to improvements in boilers, and has among its objects the production of a boiler of the kind described which is compact, durable, reliable, efficient 5 and satisfactory for use wherever found applicable.

My invention relates particularly to water tube boilers of the inclined bent tube type and has for one of its objects to so arrange 10 a superheater within the boiler that it will be normally in the path of travel of the flames and heated gases from the combustion chamber and will become highly heated thereby.

Many other objects and advantages of the construction herein shown and described will be obvious to those skilled in the art from 15 the disclosures herein given.

To this end my invention consists in the 20 novel construction, arrangement and combination of parts herein shown and described, and more particularly pointed out in the claims.

In the drawings, wherein like reference 25 characters indicate like or corresponding parts,

Fig. 1 is a sectional view of a boiler illustrating my invention;

Fig. 2 is a view taken substantially on the 30 line 2—2 of Fig. 1;

Fig. 3 is a section taken substantially on the line 3—3 of Fig. 2;

Fig. 4 is a fragmentary plan view of the 35 underside of the mud drum, and

Fig. 5 is a sectional view taken substantially on the line 5—5 of Fig. 4.

In the drawings, wherein I have illustrated the preferred embodiment of my invention, 1 indicates any suitable type of 40 setting adapted for use by a water tube boiler having a plurality of water and steam drums 2, 3 and 4 arranged horizontally therein at differing elevations, and a mud drum 5 below said steam drums and located

45 between the bridge wall 6 of the furnace and the rear wall 7. The feed water is introduced into the drum 4 at 8, and the steam is withdrawn from said series of drums at the outlet 9 of the drum 4. Drums 3 and 5 are connected by a bank of tubes 10, which are preferably set at the greatest inclination the head room will allow, in order

50 to get the maximum heating surface in said bank and use the longest length of tubes possible. The drums 2 and 5 are connected by the bank of tubes 11, the drums 2 and 3

by the bank of tubes 12, the drums 3 and 4 by the banks of tubes 13, said last-mentioned tubes generally having superheated steam flowing therethrough, and the drums 4 and 5 are connected by the bank of tubes 14. Suitable arches, fire doors, flues, access doors, etc., may be provided in the boiler, but as these do not form a part of my present invention, no description thereof is deemed necessary.

Baffles 16—30—31 or their equivalents may be arranged in the boiler so as to direct the flames and the heated gases from the combustion chamber 15 to travel in a pre- 70 determined manner, said direction normally taking the path of the full line arrows shown in Fig. 1.

Adjacent the bottom of the furnace and 75 extending from adjacent the bridge wall 6 to the rear wall 7, I have arranged a superheater, comprising a bank of U-shaped pipes or tubes 18, having headers 19 at one end. One of the headers is connected by a conduit 20, so as to communicate with the 80 outlet 9 of the steam drum 4, whereby the steam will flow downwardly through the pipe 20 and through the superheater in the direction shown by the arrows, at which point it may be taken off and delivered to 85 any suitable mechanism.

Intermediate the mud drum 5 and the bank of tubes 18 comprising the superheater, I have arranged a protective enclosure 23, preferably in the form of a chambered 90 receptacle engaging both the drum and the top of the superheater, and in which the blow off pipes 21 and 22 of the mud drum are positioned. The casing 23 is preferably made of refractive material, as fire clay, fire 95 brick or the like, so as not to become injured by the baking of the mud and sediment in the drum and heat coming in contact therewith, and preventing the blow off connections from burning out. The superheater 100 operates substantially similar to any superheater, and in the particular location shown, while the same may, if desired be flooded when firing up the boiler, drained, blown off, etc., by virtue of its location, water therein or 105 condensed therein when the boiler is cold will be turned to steam when the boiler is fired.

From the foregoing description it will be 110 seen that I have provided a boiler wherein the superheater is readily accessible and the superheating tubes are so arranged that they

will be normally in the path of the hot gases passing over the bridge wall from the combustion chamber, thus superheating the steam to a high degree.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a boiler, a combustion chamber at the front thereof, a bridge wall, an upper forward transverse steam drum, an upper rear transverse steam drum, a transversely extending mud drum located at the rear part of the boiler in spaced relation with the bottom and rear wall thereof, a bank of tubes extending forwardly from the mud drum to the front part of the boiler above the combustion chamber and connecting the mud drum and the forward upper steam drum, banks of tubes connecting the rear steam drum to the forward steam drum and to the mud drum, baffling means for directing the heated gases from the combustion chamber beneath the mud drum, and a superheater arranged below the mud drum and extending adjacent the rear wall of the boiler, the superheater being connected with the upper rear steam drum.

2. In a boiler, a combustion chamber at the front thereof, a bridge wall, an upper forward transverse steam drum, an upper rear transverse steam drum, a transverse mud drum located at the lower part of the boiler back of the bridge wall and spaced therefrom and from the bottom and rear wall of the boiler, a bank of tubes extending forwardly from the mud drum above the bridge wall and connecting the mud drum and forward upper steam drum, banks of tubes connecting the rear steam drum to the forward steam drum and to the mud drum, baffling means for directing the heated gases from the combustion chamber beneath the mud drum, and a superheater arranged back of the bridge wall below the mud drum and extending adjacent the rear wall of the

boiler, the superheater being connected with the upper steam drum.

3. In a boiler, a combustion chamber at the front thereof, a bridge wall, an upper forward transverse steam drum, an upper rear transverse steam drum, a transversely extending mud drum located at the rear part of the boiler in spaced relation with the bottom and rear walls thereof, a bank of tubes extending forwardly from the mud drum to the front part of the boiler above the combustion chamber and connecting the mud drum to the forward upper steam drum, banks of tubes connecting the rear steam drum to the forward steam drum and to the mud drum, baffling means for directing the heated gases from the combustion chamber beneath the mud drum, a superheater arranged below the mud drum and extending adjacent the rear wall of the boiler, the superheater being connected with the upper steam drum, and a refractory material positioned to engage between said superheater and the mud drum.

4. In a boiler, a combustion chamber at the front thereof, a bridge wall, an upper forward transverse steam drum, an upper rear transverse steam drum, a transversely extending mud drum located at the rear part of the boiler in spaced relation with the bottom and rear wall thereof, the mud drum being provided with blow off pipes, a bank of tubes extending forwardly from the mud drum to the front part of the boiler above the combustion chamber and connecting the mud drum and the forward upper steam drum, banks of tubes connecting the rear steam drum to the forward steam drum and to the mud drum, baffling means for directing the heated gases from the combustion chamber beneath the mud drum, a superheater arranged below the mud drum and extending adjacent the rear wall of the boiler, the superheater being connected with the upper rear steam drum, and a protective casing of refractory material interposed between the superheater and the mud drum and providing a chamber receiving the blow off pipes of the mud drum.

In testimony whereof, I have hereunto signed my name.

RALEIGH J. ADAMS.
